UNITED STATES PATENT OFFICE

WILLIAM FREDRICK HAACK, OF BERWYN, ILLINOIS, ASSIGNOR TO WESTERN ELECTRIC COMPANY, INCORPORATED, OF NEW YORK, N. Y., A CORPORATION OF NEW YORK

TOOL

Application filed October 15, 1926. Serial No. 141,721.

This invention relates to tools, and more particularly to tools for separating closely confined and compacted assemblies of layered material.

It is the practice in telephone exchanges, for example, to connect the switchboards with the cables terminating in the exchange by a cable assembly comprising a plurality of rows of separate layers of cables, the several layers comprising each row being unbound and arranged in close contact one with the other in vertical order at the rear of the switchboard in close relation thereto and extending longitudinally thereof. The individual conductors of the different cables composing the layers are connected to their respective terminals on the switchboard frame by a short length of conductor, the whole multiple cable assembly being supported upon open racks. The short lengths of conductors connecting the cable assembly and the terminals on the switchboard frame may, in some cases, due to various causes, become disconnected or broken and to repair them the cables must be separated sufficiently to gain access to the area of the needed repair. It is also sometimes desirable to separate the cables in order to more easily inspect the connections between the conductors and the cables.

The primary object of this invention is the provision of an improved tool for readily and efficiently separating closely confined and compacted assemblies of layered material.

In accordance with the general features of this invention there is provided in one embodiment thereof a wedging tool comprising two telescopic members which form a very flat wedge when in a closed position, the members being provided with means for regulating the separation therebetween comprising an oppositely threaded compound screw operatively connected to the members and providing means whereby the wedging tool may be opened or closed by opposite rotations of the screw.

Other objects and advantages of this invention will more fully appear from the following detailed description taken in connec-

tion with the accompanying drawings, in which

Fig. 1 is a side view of a wedging tool embodying the features of this invention, partly in section and shown in its operated or open position;

Fig. 2 is a fragmentary plan view thereof, partly in section;

Fig. 3 is a schematic view, partly in section, of a cable assembly showing the pointed end portion of the wedge at the beginning of its introduction between layers of a multiple cable; and

Fig. 4 is a view similar to that of Fig. 3 with the wedge fully introduced and in an operated position between layers of the cable.

In Figs. 3 and 4 the wedging tool is illustrated as being used to separate the layers of a telephone cable assembly comprising a plurality of individual cables, each being shown in rectangular cross-sectioned form arranged in close contact with each other in vertical and horizontal layers and extending longitudinally of a telephone apparatus (not shown). The individual conductors of the cables of the assembly are connected to their respective terminals on the switchboard frame by short length conductors shown as extending from the left side of the cable assembly. The cable assembly is supported on a horizontal shelf carried by upright members.

The wedging tool of this invention preferably consists of two pointed channel members 10 and 11 which, when in a closed position as shown in Fig. 3, are telescoped in order to form a wedge of minimum thickness in order to facilitate entry of the wedge between the layers of the multiple cable. In the channel member 10 there is mounted a compound screw 12 which is journaled in supports 13 and 14 securely fastened in the channel member by any suitable means, as by screws. The compound screw 12, the threads of which run in opposite directions, carries nuts 16 and 17 which are moved simultaneously in opposite directions upon the operation of the screw, which movement may be effected by means of an operating mechanism shown in Fig. 2 and which will be here-

inafter described in detail. On each nut 16 and 17 there is pivotally mounted a pair of levers 18, 19, and 20, 21, respectively. The opposite ends of the levers are pivoted to the side flanges of the channel member 11 by means of pins 22 and 23 which are slidably arranged in slots 24 and 25 as shown in Fig. 1. Each pair of levers 18, 19, and 20, 21 is associated with a pair of camming members or arms 26, 27, and 28, 29, respectively. The camming arms are pivoted on headed pins 40, 41, 42, and 43, respectively, secured to the flanges of the channel member 10 and normally held in engageable relation with the free end portions of their respective associated levers and are drawn by means of tension springs 30 and 31 which resiliently hold the camming arms against the bottom surface of channel member 10 as shown in Fig. 1 when the wedge is open, thus holding them in position ready to be engaged by their respective levers upon closure of the wedge.

The compound screw 12 is held against longitudinal movement in the supports 13 and 14 by means of end thrust collars 32 and 33 which may be secured to the body portion of the screw in any well known manner, as by screws. To the right end of the screw 12 is keyed a ratchet wheel 34, provided with square teeth for engagement with a spring pressed pawl 35. This pawl is slidably and rotatably arranged in a crank arm 36 loosely mounted on the end portion of the screw 12 adjacent the ratchet wheel 34. The crank 36 is held in position by an end thrust bearing consisting of a flat washer 37 and a nut 38. The pawl 35 is provided at one end with an enlarged knurled portion 39 for manually rotating the pawl, while the opposite end of the pawl is so shaped that it will slide over the teeth of the wheel 34 in one direction and engage the teeth to rotate the wheel in the opposite direction. The knurled portion 39 permits moving the pawl into position to render the movement of the crank 36 in either desired direction effective, whether for opening or closing the wedging tool.

The manner in which a multiple cable assembly may be separated by means of the tool of this invention is as follows: The wedge in its closed position is inserted in a direction transversely of the cables by manually pushing and working it into position and, as shown in Fig. 3, has been partly introduced between the layers of the multiple cable it is desired to separate, while the position thereof indicated in dotted outline shows it fully introduced and ready for operation. The pawl 35 is then rotated into position to render the movement of crank 36 effective to turn the screw 12 for moving the nuts 16 and 17 toward one another. The movement of nuts 16 and 17 forces the free end portions of the levers 18, 19, 20 and 21 against their respective associated camming arms 26, 27, 28

and 29 which, due to the angle of contact they make with their associated levers, deviate the levers from their ineffective position to start the opening of the wedge members. The levers are moved by the camming arms a small angular distance after which they become directly responsive to the action of the screw to the maximum opening between the channel members, in which position the member 11 is disposed at a slight angle to the member 10 as clearly shown in Fig. 4 to prevent the tensioning of the short lengths of conductors, which it will be apparent would occur if the movement upwardly of the member 11 was parallel to the member 10.

For returning the wedging members to their normal telescoped or closed position, the pawl 35 is moved manually half a turn in order to render the crank 36 effectively in a direction opposite to that above described. The movement of the nuts 16 and 17 away from each other moves the main levers into the position indicated in dotted outline in Fig. 1, in which position the free end portions of the levers re-engage their respective cam arms which are now rotated against the tension of springs 30 and 31 into a position substantially parallel to the length of the channel members, also shown in dotted outline. The slots 24 and 25 in which the pins 22 and 23 are guided are made of such a length as to permit the movement of the levers 18, 19, 20 and 21 to a substantially horizontal position when the channel members are telescoped. Where working space is ample the crank 36 may be rotated to operate the screw 12 in either direction, but in the case of limited working space or interference otherwise the screw may be operated also in either direction by oscillating the crank 36 through the use of the ratchet and pawl arrangement hereinbefore described. In addition other arrangements might be employed for operating the screw 12.

What is claimed is:

1. A tool comprising a plurality of members, one of which is telescopic relative to the others, the plurality of members normally forming a comparatively narrow edge at one end for insertion between two elements, a linkage reciprocally and pivotally connected at opposite ends to each of the members, and means operatively associated with the members and operatively connected to the linkage for causing a relative movement between the members to separate the cooperating narrow edges thereof.

2. A tool comprising a plurality of members normally forming a comparatively narrow edge at one end for insertion between two elements, a linkage reciprocally and pivotally connected at opposite ends to each of the members, revolvable means operatively associated with the members, means for transmitting motion from the revolvable

- means to the linkage for causing a relative movement between the members to separate the cooperating narrow edges thereof, and means for operating the revolvable means.
5. A tool comprising a plurality of members normally forming a comparatively narrow edge at one end for insertion between two elements, a linkage pivotally connected to the members, means operatively associated with the members and operatively connected to the linkage for causing a relative movement between the members to separate the cooperating narrow edges thereof, and means operatively associated with the linkage normally tending to actuate it to an operative position.
10. A tool comprising a plurality of members normally forming a comparatively narrow edge at one end for insertion between two elements, a plurality of links reciprocally and pivotally connected at opposite ends to separated portions of the members, and means carried by one of the members and operatively connected to the linkage for causing a relative movement between the members to separate the cooperating narrow edges thereof.
15. A tool comprising a pair of members normally forming a comparatively narrow edge at one end for insertion between two elements, a compound screw operatively associated with the members, means for rotating the screw, and a plurality of actuating means for the members, operable in reverse directions through the movement of the screw for separating the members.
20. A wedging tool comprising a pair of members normally forming a wedge at one end for insertion between two elements, a compound screw operatively associated with the members, means for rotating the screw, a plurality of levers associated with the members, means for transmitting motion from the screw to the levers to move them in a path longitudinally of the members, and means disposed in the path for changing the direction of movement of the levers for causing a relative movement between the members to separate the cooperating wedge ends thereof.
25. A wedging tool comprising a pair of members normally forming a wedge at one end for insertion between two elements, a compound screw operatively associated with the members, means for rotating the screw in either direction, a plurality of levers engaging the members, means for transmitting motion from the screw to the levers, camming arms normally disposed in engageable relation with the levers and effective upon a limited movement thereof for separating the cooperating wedge ends of the members, and means for holding the arms in position wherein the rotation of the screw in one direction is effective to cause the engagement of the arms by the levers for closing the members.
30. A wedging tool comprising a pair of members normally forming a wedge at one end for insertion between two elements, a plurality of actuating means for the members, a compound screw journaled upon one of the members, means for rotating the screw in either direction comprising a ratchet wheel mounted on the screw, a handle and a reversible pawl for transmitting motion from the handle to the wheel, and a plurality of elements operable in reverse directions for transmitting motion from the screw to the actuating means to separate the members.
35. A wedging tool comprising a pair of telescopic channel members normally forming a wedge at one end for insertion between two elements, a differentially threaded screw journaled upon one of the members, means for rotating the screw in either direction comprising a ratchet wheel mounted on the screw, a handle and a reversible pawl for transmitting motion from the handle to the wheel, a plurality of levers engaging the members, means for transmitting motion from the screw to the levers, camming arms normally disposed in engageable relation with the levers and effective upon a limited movement thereof for separating the co-operating wedge ends of the members, and means for holding the arms in position wherein the movement of the screw in the opposite direction is effective to cause the re-engagement of the arms by the levers for telescoping the members.
40. A tool for separating elements comprising a plurality of element engaging members normally forming a comparatively narrow edge at one end for insertion between the elements, a linkage interconnecting the members designed upon actuation to cause a relative inclined separation of the members, the members being closer at their narrow edges upon separation, and means for actuating the linkage.
45. In witness whereof, I hereunto subscribe my name this 27th day of September, A. D. 1926.
